To all whom it may concern:

Be it known that I, Frank G. Karg, a citizen of the United States and a resident of the city of Chicago, in the county of Cook and State of Illinois, have invented a new, original, and ornamental Design for a Package or Similar Article, of which the following is a specification, reference being had to the accompanying drawing, forming a part thereof.

Figure 1 is a front elevational view of the package or similar article showing my new design, with the locking tab inserted in the slot;

Figure 2 is a side elevational view thereof;

Figure 3 is a front elevational view thereof, similar to that shown in Figure 1, but with the

locking tab inserted behind the part of the package having the slot, for purposes of better illustration; and

Figure 4 is an enlarged bottom plan view thereof.

The side opposite to that shown in Figures 1 and 3 is plain.

The characteristic feature of the design resides in the package shown having a fluted lower margin, as indicated in the drawing.

I claim:

The ornamental design for a package or similar article, as shown and described.
